UNITED STATES PATENT OFFICE.

GEORGE R. CUDLIPP, OF LOS ANGELES, CALIFORNIA.

DESIGN FOR A TOY CASKET.

Application filed April 16, 1925. Serial No. 13,142. Term of patent $3\frac{1}{2}$ years.

To all whom it may concern:

Be it known that I, GEORGE R. CUDLIPP, a citizen of the United States, residing at Los Angeles, in the county of Los Angeles, State of California, have invented a new, original, and ornamental Design for Toy Caskets, reference being had to the accompanying drawing, forming a part thereof.

The figure is a perspective view of a toy casket embodying my new design.

I claim:

The ornamental design for a toy casket, as shown.

GEORGE R. CUDLIPP.
